CLAIM

The ornamental design for a multi-functional weather alert communication key chain, as shown and described.

(21) Appl. No.: **29/374,676**

DESCRIPTION

(22) Filed: **Sep. 20, 2011**

FIG. 1 is a perspective view of the front display side of the multi-functional weather alert communication key chain showing my new design;

(51) **LOC (9) Cl.** 03-01

FIG. 2 is a perspective view of the rear side with USB port retracted;

(52) **U.S. Cl.** D3/208

FIG. 3 is a perspective view of the rear side with USB port extended;

(58) **Field of Classification Search** D11/1-2,

FIG. 4 is a profile view of the base of the front display side;

D11/14, 26-29, 89-92, 44, 48, 81, 99; 63/26-28,

FIG. 5 is a right profile view of the front display side;

63/32; D3/207-212; D8/16, 38, 347, 348;

FIG. 6 is the front display profile view;

70/456 B, 457, 458; 206/37.1; D21/576,

FIG. 7 is the rear side profile view;

D21/593, 594, 606, 609, 610, 611, 659, 660;

FIG. 8 is the profile view of the rear side; and,

706/931

FIG. 9 is the top profile view of the rear side.

See application file for complete search history.

(56) **References Cited**

The broken line showing of a key ring in FIGS. 1 and 6 is included for the purpose of illustrating environmental matter and forms no part of the claimed design.

U.S. PATENT DOCUMENTS

The present invention encompasses a small portable key chain device which receives disaster and/or radio broadcast worldwide.
